Attorney, Agent, or Firm—Dorr, Carson, Sloan & Birney,
P.C.[57] **CLAIM**

The ornamental design for a bollard cap, as shown and described.

DESCRIPTION

FIG. 1 is a front perspective view of a bollard cap showing my new design.

FIG. 2 is a front elevational view of the bollard cap, with the rear elevational view being the same as FIG. 1.

FIG. 3 is a left side elevational view of the bollard cap, with the right side elevational view being the same as FIG. 3.

FIG. 4 is a top plan view of the bollard cap.

FIG. 5 is a bottom plan view of the bollard cap; and,
FIG. 6 is a cross-sectional view of the bollard cap.
